(57) **CLAIM**

The ornamental design for a depressible finger-worn ring, as shown and described.

DESCRIPTION

FIG. 1 is a perspective view of the depressible finger-worn ring according to one embodiment;

FIG. 2 is a top plan view of the depressible finger-worn ring according to one embodiment;

FIG. 3 is a bottom view of the depressible finger-worn ring according to one embodiment;

FIG. 4 is a left side view of the depressible finger-worn ring according to one embodiment;

FIG. 5 is a right side view of the depressible finger-worn ring according to one embodiment;

FIG. 6 is a front elevation view of the depressible finger-worn ring according to one embodiment;

FIG. 7 is a rear elevation view of the depressible finger-worn ring according to one embodiment;

FIG. 8 is a cross-section view of the depressible finger-worn ring of FIG. 2 viewed along line A-A;

FIG. 9 is a perspective view of the depressible finger-worn ring according to another embodiment;

FIG. 10 is a top plan view of the depressible finger-worn ring according to another embodiment;

FIG. 11 is a bottom view of the depressible finger-worn ring according to another embodiment;

FIG. 12 is a left side view of the depressible finger-worn ring according to another embodiment;

FIG. 13 is a right side view of the depressible finger-worn ring according to another embodiment;

FIG. 14 is a front elevation view of the depressible finger-worn ring according to another embodiment;

FIG. 15 is a rear elevation view of the depressible finger-worn ring according to another embodiment; and,

FIG. 16 is a cross-section view of the depressible finger-worn ring of FIG. 10 viewed along line B-B.

The broken dashed lines showing in FIGS. 8-16 are included for illustrating portions of the depressible finger-worn ring that form no part of the claimed design.

1 Claim, 8 Drawing Sheets
